(57) **ABSTRACT**

A new and distinct cultivar of *Helleborus* plant named 'HL 1014' characterized by its upright to somewhat outwardly spreading and mounded plant habit; moderately vigorous to vigorous growth habit; dark green-colored leaflets with lighter green-colored venation; freely flowering habit; light yellowish green-colored flowers; and good garden performance.

2 Drawing Sheets

1

Botanical designation: *Helleborus niger* X *Helleborus x hybridus*.

Cultivar denomination: 'HL 1014'.

STATEMENT REGARDING PRIOR
DISCLOSURES BY INVENTOR/APPLICANT

An European Community Plant Breeder's Rights application for the instant plant was filed by the Inventor/ Applicant, Mr. Josef Heuger of Glandorf, Germany, on Dec. 1, 2022, application number 2022/2748. Foreign priority is not claimed to this application.

The Inventor/Applicant asserts that no publications nor advertisements relating to sales, offers for sale or public distribution occurred more than one year prior to the effective filing date of this application. Any information about the claimed plant would have been obtained from a direct or indirect disclosure from the Inventor or Applicant. Inventor/ Applicant claims a prior art exception under 35 U.S.C. 102(b)(1) for disclosure and/or sales prior to the filing date but less than one year prior to the effective filing date.

BACKGROUND OF THE INVENTION

The present invention relates to a new and distinct cultivar of *Helleborus* plant, botanically known as *Helleborus niger* X *Helleborus x hybridus* and hereinafter referred to by the name 'HL 1014'.

The new *Helleborus* plant is a product of a planned breeding program conducted by the Inventor in Glandorf, Germany. The objective of the breeding program was to create new uniform *Helleborus* plants with unique and attractive plant habit, leaf and flower coloration and tolerance to biotic and abiotic stresses.

The new *Helleborus* plant originated from a cross-pollination conducted by the Inventor in Glandorf, Germany in December, 2014 of a proprietary selection of *Helleborus niger* identified as code number P573, not patented, as the female, or seed, parent and a proprietary selection of *Hel-*

leborus x hybridus identified as code number O1524, not patented, as the male, or pollen, parent. The new *Helleborus* plant was discovered and selected by the Inventor as a single flowering plant from within the progeny of the stated cross-pollination grown in a controlled greenhouse environment in Glandorf, Germany in December, 2016.

Asexual reproduction of the new *Helleborus* plant by in vitro axillary meristem culture in a controlled environment in Glandorf, Germany since April, 2017 has shown that the unique features of this new *Helleborus* plant are stable and reproduced true to type in successive generations.

SUMMARY OF THE INVENTION

Plants of the new *Helleborus* have not been observed under all possible combinations of environmental conditions and cultural practices. The phenotype may vary somewhat with variations in environmental conditions such as temperature and light intensity without, however, any variance in genotype.

The following traits have been repeatedly observed and are determined to be the unique characteristics of 'HL 1014'.
25 These characteristics in combination distinguish 'HL 1014' as a new and distinct *Helleborus* plant:

1. Upright to somewhat outwardly spreading and mounded plant habit.
2. Moderately vigorous to vigorous growth habit.
3. Dark green-colored leaflets with lighter green-colored venation.
4. Freely flowering habit.
5. Light yellowish green-colored flowers.
6. Good garden performance.

Plants of the new *Helleborus* differ from plants of the female parent selection in the following characteristics:

1. Leaflets of plants of the new *Helleborus* are darker green in color than leaflets of plants of the female parent selection.

2. Flowers of plants of the new *Helleborus* are darker yellowish green in color than flowers of plants of the female parent selection.

Plants of the new *Helleborus* differ from plants of the male parent selection in the following characteristics:

1. Leaflets of plants of the new *Helleborus* are darker green in color than leaflets of plants of the male parent selection.
2. Flowers of plants of the new *Helleborus* are darker yellowish green in color than flowers of plants of the male parent selection.

Plants of the new *Helleborus* can also be compared to plants of *Helleborus niger* 'COSEH210', disclosed in U.S. Plant Pat. No. 21,048. In side-by-side comparisons, plants of the new *Helleborus* differ primarily from plants of 'COSEH210' in the following characteristics:

1. Plants of the new *Helleborus* have larger leaves than plants of 'COSEH210'.
2. Plants of the new *Helleborus* have larger flowers than plants of 'COSEH210'.

BRIEF DESCRIPTION OF THE PHOTOGRAPHS

The accompanying colored photographs illustrate the overall appearance of the new *Helleborus* plant showing the colors as true as it is reasonably possible to obtain in colored reproductions of this type. Colors in the photographs may differ slightly from the color values cited in the detailed botanical description which accurately describe the colors of the new *Helleborus* plant.

The photograph on the first sheet (FIG. 1) is a side perspective view of a typical flowering plant of 'HL 1014' grown in a container.

The photograph on the second sheet (FIG. 2) is a close-up view of typical flowers of 'HL 1014'.

DETAILED BOTANICAL DESCRIPTION

The aforementioned photographs and following observations, measurements and values describe plants grown during the early spring in 17-cm containers in a glass-covered greenhouse in Glandorf, Germany and under cultural practices typical of commercial *Helleborus* production. During the production of the plants, day temperatures ranged from 12 C to 32 C and night temperatures ranged from 5 C to 12 C. Plants were 48 weeks old when the photographs were taken and 14 months old when the description was taken. In the following description, color references are made to The Royal Horticultural Society Colour Chart, 2015 Edition, except where general terms of ordinary dictionary significance are used.

Botanical classification: *Helleborus niger* X *Helleborus* x *hybridus* 'HL 1014'.

Parentage:

Female, or seed, parent.—Proprietary selection of *Helleborus niger* identified as code number P573, not patented.

Male, or pollen, parent.—Proprietary selection of *Helleborus* x *hybridus* identified as code number 01524, not patented.

Propagation:

Type.—In vitro axillary meristem culture.

Time to initiate roots, winter.—About 55 days at temperatures about 12 C.

Time to produce a rooted young plant, winter.—About 170 days at temperatures ranging from about 4 C to 15 C.

Root description.—Thick to thin, fleshy; typically white to brownish in color, actual color of the roots is dependent on substrate composition, water quality, fertilizer type and formulation, substrate temperature and physiological age of roots.

Rooting habit.—Low branching; sparse.

Plant description:

Plant and growth habit.—Herbaceous perennial; upright to somewhat outwardly spreading and mounding plant habit with flowers held above the foliar plane; plant shape, roughly globular; moderately vigorous to vigorous growth habit and moderate growth rate.

Plant height, soil level to top of foliar plane.—About 25.9 cm.

Plant height, soil level to top of flowers.—About 49.8 cm.

Plant diameter (area of spread).—About 55.5 cm.

Leaf description:

Arrangement.—Leaves arranged in a basal rosette; leaves palmately compound with typically five leaflets per leaf.

Leaf length.—About 19.6 cm.

Leaf width.—About 20.2 cm.

Leaflet length.—About 11.4 cm.

Leaflet width.—About 6.7 cm.

Leaf shape.—Palmate; roughly reniform in outline.

Leaflet shape.—Broadly elliptic to ovate or obovate.

Leaflet apex.—Acute to broadly acute.

Leaflet base.—Attenuate.

Leaflet margin.—Serrate; coarsely undulate.

Leaflet texture and luster, upper and lower surfaces.—Smooth, glabrous; coriaceous and tough; slightly glossy.

Leaflet venation pattern.—Pinnate and reticulate.

Leaflet color.—Developing leaflets, upper surface: Close to 137A; towards the base, small dots, close to N186C. Developing leaflets, lower surface: Close to 146A to 146B. Fully developed leaflets, upper surface: Slightly darker than a blend of 139A and 147A; at the base, tinged with close to 200A; venation, close to 144A. Fully developed leaflets, lower surface: Close to 147B; venation, close to 145A.

Petioles.—Length: About 13.4 cm. Diameter: About 7 mm by 8 mm. Strength: Strong. Texture and luster, upper and lower surfaces: Smooth, glabrous; matte to slightly glossy. Color, upper and lower surfaces: Close to 146B; covered with fine dots, close to 200B.

Flower description:

Flower shape and habit.—Single rotate bowl-shaped flowers arranged in panicles; freely flowering habit with about three flowers per inflorescence and about 42 flowers and flower buds per plant; flowers face mostly outwardly.

Fragrance.—None detected.

Natural flowering season.—Plants begin flowering about ten months after planting; plants flower naturally from late winter into the early spring in Germany.

Flower longevity on the plant.—About ten days; sepals persistent, other flower parts are not persistent.

Flower buds.—Length: About 2.1 cm. Diameter: About 1.2 cm. Shape: Ovate. Texture and luster: Smooth, glabrous; matte. Color: Close to 149C; towards the apex, close to 154D; at the base, close to 145A.

Inflorescence height (including peduncle).—About 5 49.2 cm.

Inflorescence diameter.—About 20.4 cm.

Flower diameter.—About 7.5 cm.

Flower depth.—About 3.5 cm.

Petals.—All petals are transformed into nectaries. 10

Sepals.—Quantity and arrangement: About five, arranged in a single whorl. Length: About 4.7 cm. Width: About 3.4 cm. Shape: Broadly ovate; slightly concave. Apex: Acute to broadly acute. Base: Cuneate. Margin: Entire; slightly undulate. Texture and luster, upper surface: Smooth, glabrous; matte. Texture and luster, lower surface: Smooth, glabrous; matte to slightly glossy. Color: When opening, upper and lower surfaces: Close to between 150D and 20 154D; at the base, close to 144B. Fully opened, upper and lower surfaces: Close to 150D; at the base, close to 144D; venation, similar to lamina colors; color does not change with subsequent development.

Flower bracts.—Quantity per flower: Typically one. 25 Length: About 6.4 cm. Width: About 2.4 cm. Shape: Broadly ovate to oblong. Apex: Acute to three-lobed. Base: Truncate to cuneate. Margin: Mostly entire; distally, occasionally, finely serrate; coarsely undulate. Color, upper surface: Close to NN137B. Color, lower surface: Close to a blend of 146B and 147B; 30 midvein, tinged with close to 182B.

Peduncles.—Length: About 39.7 cm. Diameter: About 7.5 mm to 8 mm. Aspect: About 20 degrees from vertical. Strength: Strong. Texture and luster: Smooth, glabrous; moderately glossy. Color: Close to 144B; heavily covered with fine dots, close to 183A to 183B.

Pedicels.—Length: About 3 cm. Diameter: About 3 mm. Aspect: About 30 degrees from peduncle axis. 40 Strength: Moderately strong. Texture and luster: Smooth, glabrous; moderately glossy. Color: Close to 146D; heavily covered with fine dots, close to 182B.

Reproductive organs.—Stamens: Quantity per flower: About 60. Filament length: About 1.4 cm. Filament color: Close to 150D. Anther shape: Double and broadly reniform; basifixated. Anther size: About 2 mm by 3 mm. Anther color: Close to 151D. Pollen amount: Sparse. Pollen color: Close to 4D to lighter than 4D. Pistils: Quantity per flower: About seven to nine. Pistil length: About 1.3 cm. Stigma diameter: About 0.3 mm. Stigma shape: Club-shaped. Stigma color: Close to 157A. Style length: About 1.25 cm. Style color: Close to 150D. Ovary color: Close to 145A; adaxial rib, close to 145B. Nectaries (transformed petals): Quantity per flower: About twelve. Length: About 1.1 cm. Diameter: About 5.5 mm. Shape: Tubular, flattened; apices, obtuse. Texture and luster, inner and outer surfaces: Smooth, glabrous; slightly glossy. Color, immature, inner surface: Close to N144A; towards the apex, close to N144B. Color, immature, outer surface: Close to N144A; towards the apex, close to N144B; at the base, close to 144A. Color, mature, inner surface: Close to N144A; towards the apex, close to 151B; venation, similar to lamina colors; with subsequent development, color becoming closer to 151A, towards the apex, closer to 153C to 153D. Color, mature, outer surface: Close to N144A; towards the apex, close to 151B; at the base, close to 144A; venation, similar to lamina colors; with subsequent development, color becoming closer to 151A, towards the apex, closer to 153C to 153D and at the base, closer to 152A to 152B. Seeds and fruits: To date, seed and fruit development have not been observed on plants of the new *Helleborus*.

Garden performance: Plants of the new *Helleborus* have been observed to have good garden performance and to tolerate rain, wind, high temperatures about 35 C and to be suitable for USDA Hardiness Zones 5 through 9.

Pathogen & pest resistance: To date, plants of the new *Helleborus* have not been observed to be resistant to pathogens and pests common to *Helleborus* plants.

It is claimed:

1. A new and distinct *Helleborus* plant named 'HL 1014' as illustrated and described herein.
